UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

MINE-LOCOMOTIVE.

1,358,029.

Specification of Letters Patent. Patented Nov. 9, 1920.

Application filed January 15, 1920. Serial No. 351,600.

To all whom it may concern:

Be it known that I, WILLIAM W. SLOANE, a citizen of the United States, residing at Chicago, in the county of Cook and State 5 of Illinois, have invented an Improvement in Mine-Locomotives, of which the following is a specification:

This invention relates to improvements in mine locomotives and has for its principal 10 object to provide a new and improved machine of the above description, which is particularly adapted for use with storage batteries; although not necessarily restricted to such use.

15 The object of my invention, generally stated, is to provide a single-motor locomotive having a pair of flexibly mounted driving axles, in which the overall height of the locomotive may be reduced to a minimum, 20 so as to be particularly adaptable for use in mines.

Mine locomotives deriving electrical energy from the trolley-wire have heretofore been constructed in accordance with Patent 25 #873,442 to N. D. Levin, in which two axles are pivotally mounted on the locomotive frame in order to afford relative flexibility of the axles in following uneven track, and in which the power from a single motor 30 mounted on the frame is transmitted to the axles through a reach gear in vertical alinement with the pivot. However, it has been found that such a construction is not readily adaptable to locomotives of the storage battery type, on account of the bulk and height 35 of storage batteries which must be carried by such locomotives. As a general proposition, it is desirable to increase the length of wheelbase commensurate with any increase 40 in bulk and weight of the locomotive. In the flexible truck construction shown in the Levin patent, it will be observed that the length of wheelbase is necessarily limited by the size of the reach gear between the 45 axle gears, and that the driving mechanism is placed above the reach gear; and comparatively high on the locomotive frame. Furthermore, there is a definite relation between the height of the driving mechanism 50 and the length of wheelbase, inasmuch as any increase in the size of the reach gear, in order to increase the wheelbase, will necessitate a corresponding increase in the height of the driving mechanism and motor. If

the batteries are superposed over the driving 55 mechanism and motor located above the reach gear, arranged as shown in the Levin patent, the overall height of the locomotive is necessarily increased to an objectionable degree on account of the limited overhead 60 clearance available under usual mine conditions. On the other hand, if the batteries are placed at both sides of the motor on the ends of the locomotive frame, the wheelbase has been found to be too short to properly 65 support the loads overhanging each end, resulting in a "teetering" motion which tends to derail the locomotive. Accordingly, as will hereinafter appear, I have provided an improved construction of a single- 70 motor, flexible truck, type of battery locomotive, in which the motor and driving mechanism is lowered, and the wheelbase lengthened so that the overall height of the locomotive, including the batteries, is re- 75 duced to a minimum.

Further objects and advantages will appear from the following description of the construction of a locomotive embodying one of many forms in which my invention may 80 be incorporated.

The invention consists in the construction, combination and arrangement of parts, as will hereinafter be fully set forth in connection with the accompanying drawings, 85 and more particularly pointed out in the appended claims.

In the drawings, Figure 1 is a side view in elevation of a storage battery locomotive embodying my invention. 90

Fig. 2 is an enlarged top view of the central portion of the locomotive frame, with the storage battery box removed.

Fig. 3 is a vertical cross section taken on line 3—3 of Fig. 2, drawn to a larger scale 95 than Fig. 2, with the battery box omitted.

Fig. 4 is an enlarged cross section taken on line 4—4 of Fig. 2 and drawn to the same scale as Fig. 3, with the battery box omitted.

Fig. 5 is a vertical cross section taken on line 5—5 of Fig. 2, illustrating details and arrangement of the driving mechanism, with a portion of one gear broken away to show the bearings thereof.

Fig. 6 is an enlarged vertical cross section 105 detail view, taken on line 6—6 of Fig. 5, illustrating details of construction of one of the gears.

Fig. 7 is a fragmentary detailed view showing the conformation of the axle gear teeth.

In the embodiment of my invention illustrated, a locomotive 1 is provided with a central frame portion 2, a pair of axles 3, 3, supporting wheels 3^a, 3^a, on said axles, and a storage battery box 4, mounted on said frame, and supported thereon by a plurality of springs 5, 5. Said battery box is adapted to contain a plurality of storage battery cells (not shown) of any standard construction, preferably arranged side by side. As will be manifest to those skilled in the art, a locomotive of the type illustrated requires a relatively large number of battery cells in order to provide sufficient capacity for operation under usual conditions. I find it desirable to arrange the battery box symmetrically with respect to the supporting axles, and extending the full width of the frame as shown, in order to properly distribute the weight of the batteries on the locomotive. The battery box may also be provided with a plurality of removable covers 4^a, 4^a, so that the batteries may be readily accessible for inspection, removal, or repairs.

The axles 3, 3, are each journaled in brackets 6, 6, which are pivotally connected to the frame 2 by horizontal disposed pivot pins 7, 7. Said pivot pins 7, 7, are preferably located in alinement with each other near one side of said frame portion 2 and above the axles, as shown in Fig. 3. The opposite unpivoted ends of the brackets 6, 6 are each provided with vertically disposed springs 8, 8, seated in recesses 9, 9, on said frame to provide resilient supports for one side of the frame and locomotive body. It will be seen that this pivoted construction allows one axle to swing in relation to the other axle so that the wheels may remain in contact with the rails during the operation of the locomotive over uneven track. In the preferred construction shown, both axles 3, 3, are pivoted, but it is manifest that substantially the same flexibility of the truck will result, if only one of the axles is mounted on a pivoted bracket, and the other axle mounted rigidly with respect to the frame.

The locomotive is driven by a single electric motor 10, housed in a suitable casing 11, preferably cast integral with the frame 2. The motor 10 is provided with an armature 12, an armature shaft 13, and bearings 13^a, 13^a, for said shaft. A brake-drum 13^b is preferably mounted on the armature shaft 13 near one end thereof.

The motor armature 12 is interposed between the axles 3, 3 and parallel therewith, so that the greatest width of the motor, represented by the pole pieces 10^a, 10^a, is lo-

cated between the axles, as shown. This arrangement allows the motor to be set as low on the frame as is practicable, as it will be seen, that the bottom wall of the motor casing 11 establishes the clearance of the locomotive over the center of the roadbed. The motor 10 may be of any approved type, the details of which need not be described for the purpose of disclosing the present invention, except to call attention to the usual form of commutator 14, and commutator brushes 15, preferably located in the end portion 12^a of the casing 11, which extends between and beyond the locomotive wheels, on one side of the frame. A removable cover plate 11^a extends over the end of the casing 11, and may be removed to allow the entire armature 12 to be taken out of said casing. Hand holes 11^b, 11^b, having covers 11^c, 11^c, hinged to said cover plate 11^a, are also provided for inspecting and adjusting the commutator brushes.

The power transmission mechanism comprises the armature shaft 13, pinion 16 on said armature shaft, two intermediate gears 17, 17, mounted on the frame on opposite sides of said armature pinion and meshed therewith, and gear wheels, 18, 18, rigidly mounted on the axles 3, 3, and each meshed with an intermediate gear 17. The arrangement is such that the pinion 16, intermediate gears 17, 17, and axle gears 18, 18, all rotate in substantially the same vertical plane as the axes of the pivots 7, 7. This arrangement of gearing allows each axle to swing on its respective pivot 7, while maintaining driving connection between the axle gear 18, and its respective intermediate gear 17, in all permissible positions of the axle.

It will be observed, however, that the main feature of the arrangement just described, is the provision of a meshed relation, at a point substantially in the same vertical plane with the axes of pivots 7, 7, between the intermediate gears 17, 17, and suitable gears carried by the brackets 6, 6, each of the last named gears having operative connection with its respective axle. In other words, my invention broadly covers any arrangement of power transmitting mechanism carried on the brackets 6, 6, which mechanism includes a gear having continuous driving connection with an intermediate gear mounted on the frame in the manner shown. I do not, therefore, wish to be understood as limiting myself to the particular form of gearing which I have chosen herein as the preferred embodiment of my invention, excepting as specifically included in the appended claims.

Fig. 7 illustrates a preferred conformation of the gear teeth 31, of the axle gears 18, in which the ends 32, 32, of each tooth are slightly tapered or rounded, and the end

portions 33, 33, of the trough between the teeth, are beveled or rounded as shown, in order to permit a proper engagement of the teeth when the axle is removed out of parallelism with its respective intermediate gear 17.

The pivots 19, 19, of the intermediate gears 17, 17, are preferably positioned in approximately the same horizontal plane as the wheel axles 3, 3, so that any wear of the axle journal bearings will have no appreciable effect on the geared connection between the intermediate gears and the axle gears. I do not wish to be understood as limiting myself to this specific construction, however, except as specifically limited in the appended claims. The pivots 19, 19, of said intermediate gears comprise two stationary spindles 20, 20, each seated on one end in suitable bosses 21, 21, adjacent the motor casing, and at the other end, in downwardly depending bosses 22, 22, preferably cast integral with the frame, and secured by suitable set screws 23, 23, (see Fig. 1). Mounted on each spindle 20, 20, is a pair of annular ball bearing races 24 and 25, of any approved pattern, comprising inner races 24^a, and 25^a, and outer races 24^b, and 25^b, respectively, and provided with ball bearings 26, 26. Said ball bearing races are located on opposite sides of the central plane of rotation of the intermediate gears and their associated axle gears 18, 18, as shown. (See Fig. 6.) An annular separator ring 27 is inserted between the outer races 24^b, and 25^b. A gear body 26 having a toothed periphery 27^a, engages the outer peripheries of the races 24^b, and 25^b, said gear body being also provided with an annular flange 26^b extending over and engaging a side face of the race 25^b. A clamping ring 28 engages the oppositely disposed side face of the race 24^b and is held thereagainst by a plurality of bolts 29, 29, extending through the gear body 26 and said clamping ring, whereby the outer races 24^b and 25^b, and the separator ring 27, are firmly clamped in the gear body 26. Bearing rings 30, 30, are mounted on the spindle 20 on the outside of the inner ball races 24^a, and 25^a, respectively, said bearing rings extending slightly beyond the lateral faces of the gear to engage the bosses 21 and 22, and space the gear in place therebetween. This construction provides a bearing for radial loads, as well as any lateral thrust on the intermediate gear caused by the swinging of the wheel axles on their pivots, which thrust is transmitted through the bearing rings 30, 30, to the supporting bosses 21 or 22. Any suitable roller bearings, or similar anti-friction bearing devices may be used in place of the ball bearings above described, if desired.

From the foregoing description, it will

be clear that I have provided a driving mechanism in operable relation with two locomotive axles having relative flexibility, in which the wheelbase is made of sufficient length to permit a storage battery of the desired size to be mounted over the driving mechanism and to form with said storage battery, a locomotive suitable for operation in mines. The pivots of the axle supporting brackets, and the drive gearing in vertical alinement therewith, are mounted near one side of the locomotive and beyond the boundaries of the motor casing, and form therewith a simple, durable and compact arrangement of parts, requiring a minimum of space for the entire driving mechanism. The arrangement is such that the bearings and parts of the drive gearing are readily accessible from one side of the locomotive, and the motor parts are readily accessible from the opposite side of the locomotive, for inspection, adjustment, or removal, without necessitating the removal of the storage battery box or the supporting wheels from the frame.

Having described my invention, what I claim as new and desire to secure by Letters Patent, is:

1. A locomotive comprising a main frame, two axles, a motor mounted on said frame having its greatest width between and extending below said axles, a gear carried by said main frame intermediate said motor and one of said axles, and forming an operative connection therebetween, and means connecting the last named axles to said frame and affording movement of said axles substantially in a vertical plane, whereby said gear is maintained in driving connection with said axle in all its various positions.
2. A locomotive comprising a main frame, two axles laterally spaced apart, at least one of which is pivotally connected with said frame by a substantially horizontal pivot, an electric motor mounted on said frame having its greatest width between and extending below said axles, an armature shaft arranged substantially parallel with said axles, and a gear carried by said frame intermediate said armature shaft and said pivoted axle, and affording an operative connection whereby said axle is driven in all its various positions.
3. A locomotive having a frame, two axles laterally spaced apart, means affording movement of said axles substantially in a vertical plane independent of each other, an electric motor mounted on said frame having an armature shaft substantially parallel with the normal position of said axles, said motor having its greatest width between and extending below said axles, an operative connection between said armature shaft and each axle, and a storage

battery carried by said frame above said motor.

4. A locomotive having a frame, two axles laterally spaced apart, at least one of which is pivotally connected with said frame by a substantially horizontal pivot, an electric motor mounted on said frame and having its greatest width between and extending below said axles, and an operative connection between said motor and said axles independent of said pivot, whereby said axles are driven in all their various positions.

5. A locomotive having a frame, two axles laterally spaced apart, at least one of which is pivotally connected with said frame by a substantially horizontal pivot, an electric motor mounted on said frame and having its greatest width between and extending below said axles, an operative connection between said motor and said axles independent of said pivot, whereby said axles are driven in all their various positions, and a storage battery carried by said frame above said motor.

10. A locomotive having a frame, two axles laterally spaced apart, at least one of which is pivotally connected with said frame by a substantially horizontal pivot, an electric motor mounted on said frame

15 having an armature shaft substantially parallel with said axles, said motor having its greatest width between and extending below said axles, and an operative connection between said motor and said axles.

20 30 35 40 45 50 55 60 65 7. A locomotive having a frame, two axles laterally spaced apart, at least one of which is pivotally connected with said frame by a substantially horizontal pivot, an electric motor mounted on said frame having an armature shaft substantially parallel with said axles, said motor having its greatest width between and extending below said axles, an operative connection between said motor and said axles, and a storage battery carried by said frame above said motor.

8. A locomotive having a frame, two axles laterally spaced apart, at least one of which is pivotally connected with said frame by a substantially horizontal pivot, a gear on each of said axles, two intermediate gears substantially in line with said pivot and each having operative connection with one of said axle gears, and a motor mounted on said frame having operative connection with each of said intermediate gears.

9. A locomotive having a frame, a motor mounted thereon, two axles laterally spaced apart, at least one of which is pivotally connected near the end thereof with said frame by a substantially horizontal pivot, a gear on each of said axles, two intermediate gears substantially in line with said pivot, and each having driving connection

with one of said axle gears independent of said pivot, and an operative connection between said intermediate gears and said motor.

10. A locomotive having a frame, a motor mounted thereon, a storage battery carried by said frame, two axles laterally spaced apart, at least one of which is pivotally connected with said frame by a substantially horizontal pivot, a gear on each of said axles, two intermediate gears mounted on the frame substantially in line with said pivot, and each having driving connection with one of said axle gears, and an operative connection between said intermediate gears and said motor.

11. A locomotive having a frame, a motor carried by said frame and located on one side thereof, two axles laterally spaced apart, each mounted on a bracket pivotally connected with said frame near the other side thereof and beyond the boundary of said motor, gears on said axles, two intermediate gears mounted on said frame substantially in line with said pivots and each having operative connection with one of said axle gears, and an operative connection between said intermediate gears and said motor.

12. A locomotive having a frame, a motor mounted thereon, a storage battery carried by said frame, two axles laterally spaced apart, at least one of which is pivotally connected with said frame by a substantially horizontal pivot, a gear on each of said axles, two intermediate gears mounted on the frame substantially in line with said pivot and each having driving connection with one of said axle gears, and with said motor, said intermediate gears being on one side and beyond the boundary of said motor.

13. A locomotive having a frame, two axles laterally spaced apart, at least one of which is pivotally connected with said frame by a substantially horizontal pivot near one side thereof, an electric motor mounted on said frame having an armature shaft substantially parallel with said axles, a gear on each of said axles substantially in line with said pivots, two intermediate gears mounted on said frame, and each geared with one of said axle gears, a pinion on said armature shaft between said intermediate gears and meshed therewith, said axle gears, intermediate gears, and pinion all rotating in substantially the same vertical plane.

14. A locomotive having a frame, two axles laterally spaced apart, at least one of which is pivotally connected with said frame by a substantially horizontal pivot, a motor mounted on said frame and having its greatest width between and extending below said axles, and a train of gears affording op-

- erative connection between said motor and each axle, all of said gears being on one side and beyond the boundary of said motor.
15. A locomotive comprising a frame, two axles laterally spaced apart, at least one of which is pivotally connected with said frame by a substantially horizontal pivot, a motor mounted on said frame having its greatest width between and extending below said axles, and a train of gears mounted on said frame having an operative connection with said pivoted axle at a point substantially in line with said pivot, whereby said axle is driven in all its various positions.
- 15 16. A locomotive having a frame, a motor mounted thereon, an axle pivotally connected with said frame by a substantially horizontal pivot, a gear fixed on said axle, a second gear meshed with said axle gear, and having driving connection with said motor, both of said gears rotating in substantially the same vertical plane with the axis of said pivot, and a bearing for said second gear mounted on said frame, comprising a plurality of anti-friction bearings spaced on both sides of said vertical plane.
17. A locomotive having a frame, a storage battery carried on said frame, two axles laterally spaced apart and provided with supporting wheels, means pivotally connecting at least one of said axles with said frame near one side thereof, a motor mounted on said frame having an armature extending beyond the plane of said supporting wheels at the opposite side of said frame, and an operative connection between said armature and said axles.
18. A locomotive having a frame, a motor mounted thereon, a bracket pivotally connected to said frame and having an axle journaled therein, a gear mounted on said bracket having a driving connection with said axle, a second gear intermediate said motor and said first mentioned gear, and having an operative connection with the latter substantially in the same vertical plane with the axis of said pivoted connection, and a bearing for said second gear on said frame, comprising a plurality of annular anti-friction bearings spaced on both sides of said vertical plane.
19. A locomotive having a frame, a storage battery carried by said frame, two axles laterally spaced apart and provided with supporting wheels, means affording independent movement of said axles substantially in a vertical plane, an electric motor, a casing for said motor mounted on said frame and between said axles, said casing having an end portion extending laterally beyond the plane of the supporting wheels on one side of the locomotive, means in said end portion affording access to said motor, and means located at the opposite end of
- said casing affording operative connection between said motor and said axles.
20. A locomotive having a frame, a storage battery carried on said frame, two axles laterally spaced apart and provided with supporting wheels, means pivotally connecting at least one of said axles with said frame near one side thereof, a motor mounted on said frame having an armature extending beyond the plane of said supporting wheels at the opposite side of said frame, and a train of gears forming an operative connection between said armature and said axles at a point substantially in line with said pivot.
21. A locomotive having a frame, two axles laterally spaced apart, at least one of which is pivotally connected with said frame by a substantially horizontal pivot, an electric motor mounted on said frame, and having an armature interposed between and arranged substantially horizontal with the normal position of said axles, and an operative connection between said armature and said axles whereby said axles are driven in all their various positions.
22. A locomotive having a frame, two axles laterally spaced apart, and provided with supporting wheels, a storage battery carried by said frame above said axles and wheels, means affording independent movement of said axles substantially in a vertical plane, an electric motor mounted on said frame having its greatest width between and extending below said axles, and a train of gears affording operative connection between said motor and each axle; all of said gears being on one side and beyond the boundary of said motor.
23. A locomotive having a frame, two axles laterally spaced apart and provided with supporting wheels, means affording independent movement of said axles substantially in a vertical plane, an electric motor mounted on said frame having its greatest width between and extending below said axles, two gears mounted on said frame, each arranged intermediate said motor and one of said axles, and forming an operative connection therebetween; both of said gears being on one side and beyond the boundary of said motor.
24. A locomotive comprising a main frame, two axles laterally spaced apart, one of which is adapted to swing out of parallelism with the other of said axles, an electric motor mounted on said frame having an armature shaft interposed between, and substantially parallel with the normal position of said axles, and a train of gears affording an operative connection between said armature and said axles.

WILLIAM W. SLOANE.
